UNITED STATES PATENT OFFICE.

LACEY Y. WILLIAMS, OF TOLEDO, OHIO.

DUST-GUARD.

1,156,959.

Specification of Letters Patent.

Patented Oct. 19, 1915.

Application filed October 15, 1914. Serial No. 866,799.

To all whom it may concern:

Be it known that I, LACEY Y. WILLIAMS, a citizen of the United States, residing at Toledo, in the county of Lucas and State

present improvement consists in making each of the L-shaped sections of the guard of three layers of wood riveted or riveted and glued or cemented together, removing

60

driven into the central layer F of wood in the short arm, the shoulders thereon limiting the degree of penetration, and the projecting part of the staple is movable within 5 the recess of the long arm, the rivet V guiding the same in its movements and preventing the separation of the arms. One end of the spring S is secured to the short arm by an eye W through which passes one prong 10 of the staple and the other end of the coil is anchored to the long arm by an eye P and a rivet O.

The guard as thus constructed fulfills the desired requirements of relatively cheap first 15 cost, effectiveness in operation and durability.

As before stated, the best embodiment of the invention includes the union of the several sheets by glue or cement, as well as the 20 union of the same by rivets, while in some instances the rivets are sufficient when many of them are employed. Both the embodiments cure the imperfections appertaining to the guards hereinbefore mentioned and 25 constitute practical and serviceable guards and accepted as such by those skilled in the art.

What I claim is:

1. A dust guard consisting of two complementary L-shaped sections, each section having a long arm and a short arm and a semicircular bearing edge, and the said sections oppositely disposed to each other to form a substantially circular opening; both 30 of said sections comprised of sheets of wood with the grains of the wood angularly disposed and the sheets riveted together; and springs secured to the adjacent long and short arms of the sections for forcing the 35

bearing edges of the sections against a journal.

2. A dust guard consisting of two complementary L-shaped sections, each section having a long arm and a short arm and a semicircular bearing edge, and the said sections oppositely disposed to each other to form a substantially circular opening; both 45 of said sections comprised of sheets of wood with the grains of the wood angularly disposed and the sheets glued or cemented and riveted together; and spring means for forcing the bearing edges of the sections against a journal.

3. A dust guard consisting of two complementary L-shaped sections, each section 55 having a long arm and a short arm and a semicircular bearing edge, and the said sections oppositely disposed to each other to form a substantially circular opening; both 60 of said sections comprised of sheets of wood with the grains of the wood angularly disposed and the sheets riveted together; also each of said long arms being provided with a recess formed by removing a part of the central sheet of wood; a coiled spring and 65 a staple within each recess, the staple secured to a short arm and movable within the recess, and the spring anchored to the short arm at one end by the staple and at the other end to the long arm by a rivet; and 70 guiding pins or rivets passed through the long arms and the staples.

In testimony whereof I affix my signature in presence of two witnesses.

LACEY Y. WILLIAMS.
